Patented June 22, 1920.

Inventor

R.E.Uhl

By Watson E. Coleman

Attorney

UNITED STATES PATENT OFFICE.

ROBERT EMIL UHL, OF GREENFIELD, OHIO.

SUPPORTER.

1,344,068.

Specification of Letters Patent. Patented June 22, 1920.

Application filed January 24, 1920. Serial No. 353,644.

To all whom it may concern:

Be it known that I, ROBERT E. UHL, a citizen of the United States, residing at Greenfield, in the county of Highland and State 5 of Ohio, have invented certain new and useful Improvements in Supporters, of which the following is a specification, reference being had to the accompanying drawings.

This invention relates to certain improvements in spring tension devices and has relation more particularly to a structure of this general character embodied in a garment supporter, and it is an object of the invention to provide a novel and improved device 10 of this general character embodying a pocket in which is slidably arranged a looped portion of a tension cord wherein means are provided exerting the requisite tension upon the cord.

Another object of the invention is to provide a novel and improved device of this general character wherein the looped portion of the tension cord is slidably disposed through a separating member arranged with- 15 in the pocket and which member also operates to prevent the cord from unduly spreading or to assume a position wherein the looped portion of the cord will expand or separate laterally to an extent to be exposed be- 20 yond the sides of the pocket.

The invention consists in the details of construction and in the combination and arrangement of the several parts of my improved supporter whereby certain important 25 advantages are attained and the device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:

Figure 1 is a fragmentary view partly in elevation and partly in section illustrating a spring tension device constructed in accordance with an embodiment of my invention and with the parts in their normal positions;

Fig. 2 is a view similar to Fig. 1, showing certain of the parts in a second position or wherein the tension cord is under strain; and

Fig. 3 is a transverse sectional view taken through the device as herein disclosed.

As disclosed in the accompanying drawings, 1 denotes a portion of a shoulder strap as comprised in a suspender or other garment supporter and to which is connected a 60 link 2. The link 2 is also connected with a looped strap 3 or the like provided in a pocket. The lower portion of the pocket is provided with the transversely spaced openings or eyelets 4 through which is loosely directed the tension cord 5 of any ordinary or preferred construction. By this arrangement, the cord 5 forms within the looped strap or pocket 3 a loop *a*. This denotes a spreader, preferably formed with a wire 65 strand and returned at its opposite ends to provide the eyes 7 through which the cord 5 is loosely directed so that, in practice, the cord 5 may have longitudinal movement independent of the spreader 6. 75

The strands of the cord 5 will also pass through the eyes 7^a carried by the end portions of a member 6^a, said member being preferably formed of wire with its extremities returned to produce the eyes 7^a. The 80 member 6^a serves as a bearing element while the spreader 6 serves to prevent the strands of the looped portion of the cord 5 from unduly separating and is of a length to prevent said looped portion being exposed 85 exteriorly of the looped strap or pocket 3 beyond the opposite sides thereof. Sleeved upon the strands of the cord 5 within the pocket or looped strap 3 are the coil springs 8, each of said springs being interposed be- 90 tween the lower end of the looped strap or pocket 3 and an end portion of the spreader 6. Surrounding the end of the loop of the cord 5 is a coil spring 9, having its opposite end portions engaged with the end por- 95 tions of the spreader 6.

When a pull is imposed upon the cord 5, the same will freely move through the eyes 7 of the spreader 6 and at the same time places the springs 8 and 9 under compression 100 so that upon release or reduction of the strain upon the cord 5, the same will be automatically caused to move inwardly of the looped strap or pocket 3. It has been fully demonstrated in practice that the efficiency of a spring tension device of this general character has been materially increased by permitting the cord 5 to have sliding movement with respect to the spreader 6 and in conjunction with the 105 springs 8 and 9.

From the foregoing description, it is

thought to be obvious that a supporter constructed in accordance with my invention is particularly well adapted for use by reason of the convenience and facility with which it may be assembled and operated, and it will also be obvious that my invention is susceptible of some change and modification without departing from the principles and spirit thereof, and for this reason, I do not wish to be understood as limiting myself to the precise arrangement and formation of the several parts herein shown in carrying out my invention in practice except as hereinafter claimed.

15 I claim:—

1. A device of the character described comprising, in combination, a pocket, a flexible element returned on itself presenting two strands movable through the bottom of the pocket, a separating member within the pocket and through which the strands of the flexible member are slidably disposed, and separate springs sleeved upon

the strands of the flexible member and interposed between the separating member 25 and the bottom of the pocket.

2. A device of the character described comprising, in combination, a pocket, a flexible element returned on itself presenting two strands movable through the bottom of the pocket, a separating member within the pocket and through which the strands of the flexible member are slidably disposed, separate springs sleeved upon the strands of the flexible member and interposed between the separating member and the bottom of the pocket, and an additional spring surrounding the flexible member above the separating member and coacting therewith, longitudinal movement of the strands of the flexible member in one direction placing all of the springs under compression.

In testimony whereof I hereunto affix my signature.

ROBERT EMIL UHL.
